UNITED STATES PATENT OFFICE.

GEOERGE W. MASKREY, OF WILLOW RIVER, MINNESOTA.

RAILWAY-TIE.

1,074,636.

Specification of Letters Patent.

Patented Oct. 7, 1913.

Application filed March 8, 1913. Serial No. 753,124.

To all whom it may concern:

Be it known that I, GEORGE W. MASKREY, a citizen of the United States, residing at Willow River, in the county of Pine and 5 State of Minnesota, have invented certain new and useful Improvements in Railway-Ties, of which the following is a specification, reference being had to the accompanying drawings.

10 This invention relates to new and useful improvements in railway ties, and more particularly to a metallic tie for supporting the rails of a track section.

An object of this invention is the provision 15 of a tie having novel locking means for engaging the rails of the track section.

Another object of this invention is the provision of a metallic tie which can be either formed from a single casting or from 20 separate castings and suitably connected to support the rails in the desired manner.

A further object of this invention is the provision of a tie such as described, which will be comparatively simple and inexpensive to manufacture, reliable and efficient 25 in use, and readily applied to or removed from a track bed.

With the above and other objects in view, this invention resides in the novel features 30 of construction, formations, combinations and arrangements of parts to be hereinafter more fully described, claimed, and illustrated in the accompanying drawings, in which—

35 Figure 1 is a side elevation of my invention. Fig. 2 is a top plan view thereof. Figs. 3 and 4 are detail elevations of one of the brackets and the web. Figs. 5 and 6 are transverse sectional views taken on the lines 40 5—5 and 6—6 of Fig. 1.

Referring to the accompanying drawings by similar characters of reference throughout the several views, the numeral 10 designates generally my improved tie, while 11 45 indicates the rails of a track section, which consists of the usual heads 12, base flanges 13 and connecting webs 14.

My improved tie 10 consists of a base plate 15 formed from any desired material and 50 being substantially rectangular in shape. This base plate 15 is formed adjacent its opposite ends with bolt receiving apertures 16 arranged in pairs and in transverse alignment relative to the said plate 15. Supporting brackets 17 are secured to the opposite ends of the base plate 15 and each consists

of a supporting plate 18 of a length equal to the width of the base plate 15. This supporting plate 18 is formed adjacent its opposite ends with bolt receiving apertures 19 60 adapted, when the plates 18 are disposed upon the plate 15, to register with the previously described bolt receiving apertures 16. These plates are rigidly secured to the base plate 15 by bolts 20 or other similar 65 fastening devices which pass through the openings 16 and 19 and hold the plates 18 rigidly upon the base plate 15 against any undesired displacement. Transverse vertically extending flanges 21 are formed in 70 spaced relation upon each plate 18. These flanges 21 produce resultant passages 22 which register when the plates 18 are secured to opposite end of the base plate 15. Rail supporting flanges 23 are formed upon 75 the upper terminals of the flanges 21 in horizontal planes and are braced by the supporting flanges 24, which connect the opposite side edges thereof to the opposite sides of the supporting plate 18. The flanges 21 80 of each plate 18 are formed with registering bolt receiving apertures 25.

A supporting web 26 is disposed longitudinally of the base plate 15 within the 85 passages 22 of the brackets 17. The lower side of this supporting web 26 is notched, as at 27, to receive the intermediate portions of the base plates 18 which obviously hold the said web against any undesired longitudinal movement relative to the plate 15. 90 Above these notches 27, the web 26 is formed with transverse bolt receiving apertures 28 disposed when the web 26 is arranged in its normal position in registration with the previously described apertures 25. Bolts 29 95 pass through these openings 25 and 28 and retain the web 26 rigidly upon the base plate 15. The web 26 is further provided with intermediate bolt receiving apertures 30 for a purpose which will later be disclosed. 100

A locking bar 31 is arranged for engagement with the web 26 and may or may not have a longitudinally horizontal flange 32 adapted to rest upon the upper side of the web 26 while the edge of said locking bar 105 engages one side thereof. This locking bar 31 is provided adjacent its opposite ends with bolt receiving apertures 33 arranged for registration with the previously described apertures 30. Bolts or other suitable fastening devices 34 pass through these openings 30 and 33 and retain the locking 110

bar against displacement from the web 26. These bolts are inclined, as shown, to draw the bar 31 downwardly. The opposite ends of the locking bar 31 are notched, as at 35, 5 to coöperate with the notches 36 formed in the enlarged ends 37 of the web 30 to retain, by their engagement with the base flanges 13 of the rails 11, the rails of the track section in their proper position against displacement.

The tie is used as follows: After the web 26 has been secured in its proper position upon the base plate 15, by the brackets 17, and the ties are arranged in their proper 15 relative position upon the bed of the track, the rails 11 are placed upon the webs 26 and moved outwardly until they rest upon the upper edge of the web 26 and flanges 23 of the brackets. When in this position, the 20 outer base flanges of each rail engage the notches 36 provided in the webs. The locking bars are then inserted between the rails with their notches 35 in engagement with the inner base flanges 13 of the rails and its 25 flange 32 resting upon the upper edge of the web 26 between the said rails. The bolts 34 are then applied and tightened which draws the inner side of the locking bar 30 tightly into engagement with the adjacent 30 side of the web 26, thus holding the rails against any undesired movement, yet permitting the necessary expansion and contraction thereof.

It should be understood in this connection 35 that various changes in the specific details of construction of the various parts can be resorted to, and any combination of these parts may be formed integral if so desired.

From the foregoing disclosures taken in 40 connection with the accompanying drawings, it will be manifest that a metallic railway tie is provided which will fulfil all of the necessary requirements of such a device.

Having thus described the invention, what 45 I claim as new and desire to protect by Letters Patent is:

1. In a tie such as described, the combination with a base, a web disposed upon the

base, supporting brackets connecting the web and the base, and a locking bar coöperating 50 with the web.

2. In a tie such as described, the combination with a base, brackets secured to the opposite ends thereof, a supporting web disposed within said brackets, said supporting 55 web having notches in the opposite ends thereof, a locking bar engaging said web, and coöperative notches provided in the locking bar.

3. In a tie such as described, the combination with a base plate, brackets secured to the opposite ends thereof, said brackets being formed with passages, a supporting web disposed within said passages, a locking bar engaging the web, a flange formed upon 60 the locking bar to engage one edge of the supporting web and the said locking bar and web being provided with coöperative notches.

4. In a metallic tie, the combination with a base plate, brackets secured thereto, said 70 brackets consisting of supporting plates arranged for connection with the base plate and spaced flanges, a web engaging the base plate and disposed between the flanges of the brackets, said web being notched to engage the supporting plates of the brackets, and locking bars arranged for engagement 75 with the web.

5. In a metallic tie, the combination with a base plate, of brackets secured thereto, 80 said brackets each consisting of a supporting plate, spaced flanges and rail supporting flanges, a web secured to the base plate and having its ends disposed between the spaced flanges of the brackets, said web being provided with notches in the ends thereof, a locking bar arranged for engagement with the web, said bar having a flange formed thereon to engage one edge of the web, and means for bracing the rail engaging flanges. 85 90

In testimony whereof I hereunto affix my signature in the presence of two witnesses.

GEORGE W. MASKREY.
